UNITED STATES PATENT OFFICE.

GUSTAVUS A. WIKANDER, OF PORTLAND, OREGON.

ELECTROMAGNETIC DEVICE FOR OPERATING TYPE-WRITERS.

1,117,120.

Specification of Letters Patent. Patented Nov. 10, 1914.

Application filed January 18, 1908, Serial No. 411,532. Renewed April 2, 1913. Serial No. 758,488.

To all whom it may concern:

Be it known that I, GUSTAVUS A. WIKANDER, a citizen of the United States, and a resident of Portland, in the county of Multnomah and State of Oregon, have invented a new and useful Improvement in Electromagnetic Devices for Operating Type-Writers, of which the following is a specification, reference being had to the accompanying drawings as constituting a part thereof.

This application is intended as a substitution for and a continuation and completion of the certain application for Letters Patent filed by me April 14, 1906, under Serial Number 311,704, and allowed November 1, 1907.

This invention relates to that class of electro-magnetic devices designed to be used in connection with a typewriter or other key-actuated instrument for the purpose of reducing the muscular exertion of operating such instrument, and at the same time insure uniformity in the impressions of the type; and my invention has for its object to obtain a device adapted to said use which shall be perfect in action and yet simple and comparatively inexpensive to make.

My invention also has for its object to provide an actuating mechanism of the character mentioned which is applicable to any type-writer of standard make, and may be used in connection with such type-writer by merely being positioned over the type-keys thereof; and my invention also embodies the special features, hereinafter specifically set forth and claimed.

In the drawings, Figure 1 shows a partial top view of my device, also a part of the key-board of a type-writer positioned to be operated by my device, that is to say, the corresponding keys of the type-writer being shown in dotted outline; Fig. 2 is a longitudinal section through the case of my key mechanism on a line $\alpha-\alpha$; also showing the electro-magnets, armature and power transmitting connections; Fig. 3 is a sectional detail of one of the keys of my device, illustrating how the same actuates the corresponding key of the typewriter; Fig. 4 is a partial top view corresponding with the preceding figure, except that parts are broken away; Fig. 5 is a sectional detail illustrating the operation of the "shift key" of my device, such shift key being shown as depressed and resting upon, but not yet having

actuated the shift key of the typewriter; Fig. 6 is a partial perspective of the electro-magnets, the armature and connecting rod; Fig. 7 is a detail of construction, fully explained below; Fig. 8 is a section representing a modified construction of my device, hereinafter fully explained; and Figs. 9 and 10 are details of such modified construction, the last figure showing means for operating the spacing key of the typewriter.

The numerals designate the parts referred to.

My device comprises a casing 1 in which is contained the key-board, and integrally on one side thereof, being the left side as my device is shown in the drawings, is provided an integral base 2 on which are mounted the electro-magnets 3 and power-transmitting connections, later explained.

In the casing 1 are journaled a series of rockable shafts 4, 5, 6, 7, and 8, each provided with a crank 9 and all said cranks are operatively connected by a rod 10; the ends of the shafts 4 to 8 extending and said connecting rod 10 being located exterior of the wall 1^a of the casing 1. On the shaft 7 is further mounted a crank 11, connected by a rod 12 with an arm 13, rigidly mounted on a shaft 14, journaled in bearings 15, 15. There is also fixed on the shaft 14 a short arm 16, and the arms 13, 16 support the bar or armature 17 in relative position to the cores 3^a of the magnets 3. To limit the movement of the armature 17 by the spring 18, I provide a set-screw 19 (not shown in Fig. 6). The tension of the spring 18 may be regulated by an adjustment nut 20.

In the side walls of the casing 1 are provided sockets 21 and therein are contained insulating thimbles 22, in which are set the ends of a series of transverse electric contact bars 23. On the exterior of the casing 1 are mounted plates 24 provided with hinge-plates 25, in which are hinged keys 26, 100 which in their outward appearance are made to resemble the keys of a typewriter. Each of said keys comprises a horizontal member 26^a and a dependent member 26^b.

On the shafts 4, 5, 6, 7, and 8 are pivoted a series of fingers 27, having tips 27^a resting on the corresponding key 28 of the typewriter. The fingers 27 are actuated to depress the corresponding typewriter keys by the rotation of the shafts 4, 5, 6, 7 and 8 brought about by the action of the magnets 3 upon the armature 17 and connecting de-

vices; when such magnets are thrown into circuit by depressing one of the keys 26, as presently will be explained. The fingers 27 are individually locked with the shafts 4, 5, 5 etc., by the depressing touch of the finger of the hand upon a key 26, by the means more clearly illustrated in Figs. 3 and 4. The pivoted ends 27^b of the fingers 27 are bifurcated so as to straddle a spring-controlled 10 bolt 30 reciprocating in a central longitudinal bore, therefor provided in each of the horizontal members of the fingers 27. The inner end 30^a of the bolt 30 (see Fig. 7) is upset, and on said end is mounted a sleeve 31, against which bears one end of a coil-spring 32 on the bolt 30, within said bifurcation of the finger 27. The description of one finger 27 applies to all. The action of the coil-spring 32 normally projects the 20 sleeve 31, and the springs 32 are made of sufficient strength as to cause said projection of the sleeve 31 to hold the corresponding key 26 in its normal position. The lower extremity 26^c of the key 26 is curved to an arc, 25 and is located intermediate of its shaft (4) and the inner head of the bolt 30. The dependent member 26^b of the finger 26 has an adjustable contact screw 35, normally out of contact with the contact bars 23.

30 The casing 1 has slots 1^b through which to introduce a screw-driver, as indicated by arrow, to adjust contact screw 35, and therewith the length of stroke of the key. The contact bars 23 are all connected by a 35 wire 56.

Near the ends of each of the shafts 4, 5, 6, 7, and 8 are rigidly fastened projecting arms 33, connected at their outer ends by a cross-bar 34, arranged to just allow the tip 27^c of 40 the related finger 27 to pass its interior face.

When a key 26 is depressed two actions are accomplished. The bolt 30 is projected outward of the finger-tip 27^a, the parts being so arranged as to bring the projected end 45 of the bolt 30 immediately under the bar 34. Simultaneously the contact screw 35 is brought into touch with its contact bar 23 and the electric circuit is closed. This causes the magnets 3 to act and pull the armature 50 17, the movement of which is communicated by a rod 12 to a crank 11, thus rotating the shaft 7, and all the other shafts 4, 5, 6, 8 being connected with shaft 7 by their cranks 9 and connecting bar 10, there is a simultaneous rotation of all of said shafts. The rotation 55 of said shafts causes a downward movement of the arms 33 on their axis. In the case of all fingers the bolt of which has not been projected, as mentioned, the bar 34 carried at the ends of the arms 33 will freely pass over the convexed edges of the finger-tips 27^a; but in the case of the finger of which the bolt has been projected, as described, the bar 34 will bear upon the projected end of the bolt 30 beneath it and force-

bly depress the finger 27 and actuate the related key of the typewriter. As soon as the finger of the operator is removed from the key 26 depressed, the coil-spring 32 will exert its power to project the sleeve 31 against the key-extremity 26^c and move the key-lever 26 sufficiently reversely to break the contact between the contact-screw 35, carried by the key-member 26^b, and the contact-bar 23; thus instantly relieving the pressure of the finger 27 on the key of the typewriter. This release mechanism, or its equivalent, is indispensable for otherwise the action of the device would be too sluggish and cause two keys, rapidly struck in succession, to interfere.

The keys 26 and the contact bars 23 are connected with the opposite poles of a battery, or other source of electric energy.

My device may be worked with the same speed a typewriter can be operated.

The space-bar 33 is made to simulate the space-bar of a typewriter of the Remington type for example. It is supported on two space-key levers 37, (only one of which is shown) which levers are connected by a space-bar 36, like in the typewriter referred. Pressing on any part of the space-bar 36, therefore, will operate the space-bar of the typewriter.

The fingers 27 are held against shifting laterally on the bars 4, etc., by the pendent members 26^b, being inserted in the bifurcated part 27^b of said fingers.

The shift-key 38 being provided to shift 100 the type from lower to upper-case letters, in a typewriter of the class referred to, its operation is necessarily different from the remainder of the keys of my device. An illustration of the construction of my shift-key is shown in Fig. 5, the scale of which approximately agrees with that of Figs. 1 and 2. The contact bar 23^a has an insulating sleeve arranged oppositely to the screw 35^a, carried by the pendent member 38^a. 105 The screw 35^a merely serves to limit the stroke of the shift-key 38, but there is no electric contact established by the depression of the key 38; that merely projects the bolt 30; but as soon as a type-character is 110 struck and the described power devices are set into action, then the arm 33^a is depressed with the others and the shift-key 38 operates to depress the shift-key of the typewriter 115 simultaneously with the depression of the type-key of the typewriter.

The letters of the key-board of my device are arranged to conform to and substitute those of the typewriter, and my device will be operated just like the typewriter, except that only such pressure of the finger as is sufficient to overcome the tension of the coil-spring 32, is required to strike a key on the typewriter, the real work being done by the magnet, as described.

In the representation of a modified form of my device, shown in Fig. 8, the case 56 has journaled in its walls rockable shafts 39, each provided with cranks (not shown), corresponding to the cranks 9 above described; and there is also a bar connecting all the cranks, magnets, armature and operative connections, all being substantially the equivalent of the like parts of my device first above described. But in this case the fingers 40, resting on the typewriter keys 57, are locked with shafts 39 by different means than above described. Each of said fingers 40 is made with a bifurcated hinge-end 40^a, the members of which straddle a bolt 41, as shown in Fig. 8. The bolt 41 is seated in a hole therefor made in the shaft, and is controlled by a coil-spring 42, causing the head of said bolt to normally impinge against the lower concaved extremity 43^a of the key-lever 43, and by so doing holding said key-lever in its normal position. The fingers 40 are also made with shoulders 44. When a key 43 is depressed the bolt 41 will be projected forward, engage with the shoulder 44, and thus lock the finger to its shaft. Affixed under the top of the case is a conducting frame 45, having pendent resilient wipers 46. The forward movement of the pendent member 43^a, of a key will bring the same in touch with said wiper, and by so doing close the circuit: one of the circuit wires being connected to said conducting frame 45, and the other circuit wire being connected with the keys 43. The moment the depressed key 43 is released the coil-spring 42 will exert its strength to restore the operated key to normal position and simultaneously move the bolt 41 to unlock the finger from the shaft.

To provide for the immediate interruption of the circuit the instant the key 43 is relieved of pressure, each of the pendent members 43^a of the keys is made with a shoulder 47 (see Fig. 9) which bears upon the head of the bolt 41 of a depressed finger just at the moment the same has about reached its maximum depression. At that instant the power exerted by the magnets to rotate the shaft 39 will be thrown against said shoulder 47 and force the depressed key sufficiently back to break the contact between the wiper 30 and said key, and allow the spring 42, being the equivalent of spring 32, above described, to act to instantly restore the operated parts to their normal position. The contact face of the pendent key-member 43^a is concaved so as to be better adapted to slide on the head of the bolt 41 to the shoulder 47.

The finger 48 and its connections are arranged to operate the space-bar 49, of the typewriter.

The shift-key of the typewriter is operated by a key 50 (shown in its relative posi-

tion in dotted outline in Fig. 10) the same being hinged in hinge-lugs 52, provided on the exterior of the casing 56, and comprising a dependent member 50^a, adapted to co-operate with the finger-disk of the shift-key on the typewriter, as illustrated; such finger-disk being provided with a cap 51, made with a roller 52, against which the member 50^a of the shift-key bears; and the means provided in the typewriter for normally holding the shift-key in its up-position, being utilized by me for holding the shift-key 50 of my device in its normal or up-position.

The fingers 40 are held against shifting laterally on the shafts 39 by the bolts 41, projecting between the forked members 40^a.

In either form of construction of my device, the front of the casing is open so as to adapt the same to straddle the key-board of the typewriter, as illustrated in Fig. 1, and the case is provided with supporting legs 53, and with V-shaped clips 54 arranged to interlock with the rear-rail or member 55 of the typewriter frame.

The conducting frame 45 is insulated from the case 56 by insulations 59.

I claim:

1. In a device of the character described, the combination of a frame arranged to be placed over the key-board of a typewriter, a series of rockable shafts journaled transversely therein, a bank of dummy-keys pivoted in the frame, a corresponding series of fingers pivoted on said shafts, the extremities thereof adapted to rest on corresponding key-disks of the typewriter, means operated by the depression of a dummy-key, whereby the corresponding finger is locked with its shaft, so as to rotate therewith and bear upon its corresponding key of the typewriter, an electro-magnet element, and an energizing circuit therefor, normally interrupted, means operated by the depression of a dummy-key, to close said circuit, and connections between the armature of the electro-magnet and said rockable shaft, adapted to simultaneously rotate the series of shafts, and thus to actuate the finger locked with either thereof.

2. In a device of the character described, the combination of a frame arranged to be placed over the key-board of a typewriter, a series of rockable shafts journaled transversely therein, a bank of dummy-keys pivoted in the frame, a corresponding series of fingers pivoted on said shafts, the extremities thereof adapted to rest on corresponding key-disks of the typewriter, means operated by the depression of a dummy-key, whereby the corresponding finger is locked with its shaft, so as to rotate therewith and bear upon its corresponding key of the typewriter, an electro-magnet element, and an energizing circuit therefor, normally in-

- terrupted, means operated by the depression of a dummy-key, to close said circuit, connections between the armature of the electro-magnet and said rockable shaft, adapted 5 to simultaneously rotate the series of shafts, and thus to actuate the finger locked with either thereof, and means adapted to separate the circuit contacts the instant the depressed dummy-key is released.
- 10 3. In a device of the character described, the combination of a frame, a series of rockable shafts transversely journaled therein, a bank of dummy keys pivoted in the frame, a corresponding series of fingers pivoted on 15 said shafts the extremities thereof arranged to rest on corresponding key-disks of the typewriter, means including a spring-controlled member impinging against the dummy-keys and supporting the same in their 20 normal position, said means being operated by the depression of a dummy-key to lock the corresponding finger to its shaft, an electro-magnet element, insulated contacts on the frame arranged relatively to the keys, 25 said contacts and the keys being in circuit with the magnet but said contacts being interrupted until the depression of a key, connections between the armature of the magnet and said rockable shafts adapted to 30 simultaneously rotate the series of shafts and actuate the finger locked with either thereof, means adapted to separate the circuit contacts the instant the depressed dummy-key is released.
- 35 4. In a device of the character described, the combination of a frame, a series of rockable shafts journaled transversely therein, a bank of dummy-keys pivoted in the frame, each key comprising a rectangular lever 40 having a pendent member, a corresponding series of fingers pivoted on said shafts, the extremities of said fingers being arranged to rest on corresponding key-disks of the typewriter, and said fingers being further made 45 with central longitudinal cavities, spring-controlled bolts reciprocating in said cavities of the fingers and adapted to impinge against said pendent members of the dummy-keys and support the latter in their 50 normal position, said bolts being projected outwardly by the depression of a dummy-key, rigid members on said shafts arranged approximately parallel with said fingers and adapted to engage with an outwardly 55 projecting bolt of either of said fingers and actuate such finger, an electro-magnet element, insulated contacts on the frame arranged relatively to the dummy-keys, said contacts and said keys being in circuit with 60 the magnet, but the contacts being interrupted until the depression of a key, connections between the armature of the electro-magnet and said rockable shafts adapted to 65 simultaneously rotate the series of shafts and actuate the fingers engaged by the rigid

members on said shaft, means adapted to separate the circuit contacts the instant the depressed key is released.

5. In a device of the character described, the combination of a frame, a series of rockable shafts journaled transversely therein, a bank of dummy-keys pivoted in the frame, each key comprising a rectangular lever having a pendent member, a corresponding series of fingers pivoted on said shafts, the extremities of said fingers being arranged to rest on corresponding key-disks of the typewriter, and said fingers being further made with central longitudinal cavities, spring-controlled bolts reciprocating in said cavities of the fingers and adapted to impinge against said pendent members of the dummy-keys and support the latter in their normal position, said bolts being projected outwardly by the depression of a dummy-key, arms rigid on said shafts and arranged approximately parallel with said fingers, members affixed transversely to the extremities of said arms and arranged to normally pass over said pendent extremities of the fingers but engaging with an outwardly projecting bolt thereof, an electro-magnet element, insulated contacts on the frame arranged relatively to the dummy-keys, said contacts and said keys being in circuit with the magnet, but the contacts being interrupted until the depression of a key, connections between the armature of the electro-magnet and said rockable shafts adapted to simultaneously rotate the series of shafts and actuate the fingers engaged by the rigid members on said shaft, means adapted to separate the circuit contacts the instant the depressed key is released.
6. In a device of the character described, the combination of a frame, a series of rockable shafts journaled transversely therein, a bank of dummy-keys pivoted in the frame, each key comprising a rectangular lever having a pendent member, a corresponding series of fingers pivoted on said shafts, the extremities of said fingers being arranged to rest on corresponding key-disks of the typewriter, said fingers being made with central longitudinal cavities, bolts reciprocating in said cavities of the fingers, sleeves slidable on the inner ends of said bolts, coil-springs on said bolts arranged to impinge said sleeves against said pendent members of the dummy-keys to support the latter in their normal position, said bolts being projected outwardly by the depression of a dummy-key, rigid members on said shafts arranged approximately parallel with said fingers and adapted to engage with an outwardly projecting bolt of either of said fingers and actuate such finger, an electro-magnet element, insulated contacts on the frame arranged relatively to the dummy-keys, said contacts and said keys being in circuit with the magnet, but the contacts being interrupted until the depression of a key, connections between the armature of the electro-magnet and said rockable shafts adapted to simultaneously rotate the series of shafts and actuate the fingers engaged by the rigid

- ing in circuit with the magnet, but the contacts being interrupted until the depression of a key, connections between the armature of the electro-magnet and said rockable shafts adapted to simultaneously rotate the series of shafts and actuate the fingers engaged by the rigid members on said shaft, means adapted to separate the circuit contacts the instant the depressed key is released.
7. In a device of the character described, the combination of a frame, a series of rockable shafts journaled transversely therein, a bank of dummy-keys pivoted in the frame, each key comprising a rectangular lever having pendent members, a corresponding series of fingers pivoted on said shafts, the inner ends of said fingers being bifurcated and straddling said pendent members of the dummy-keys, and the extremities of said fingers being arranged to rest on corresponding key-disks of the typewriter, and said fingers having central longitudinal cavities, bolts reciprocating in said cavities of the fingers, sleeves slidable on the inner ends of said bolts, coil-springs on said bolts and arranged to impinge said sleeves against said pendent members of the dummy-keys to support the latter in their normal position, said bolts being outwardly projected by the depression of a dummy-key, rigid members on said shafts arranged approximately parallel with said fingers and adapted to engage with an outwardly projected bolt of either of said fingers and actuating such finger, an electro-magnet element, insulated contacts on said frame arranged relatively to the keys, said contacts and said keys being in circuit with the magnet, but the contacts being interrupted until the depression of a key, connections between the armature of the electro-magnet and said rockable shafts adapted to simultaneously rotate the series of shafts and actuate the finger engaged by the rigid members of said shafts, means adapted to separate the circuit contacts the instant the depressed key is released.
8. In a device of the character described, the combination of a frame, a series of rockable shafts journaled transversely therein, a bank of dummy-keys pivoted in the frame, each key comprising a rectangular lever having a pendent member, a corresponding series of fingers pivoted on said shafts, said fingers being made with central longitudinal cavities, bolts reciprocating in said cavities, sleeves slidable on the inner ends of said bolts, coil-springs on said bolts arranged to impinge said sleeves against said pendent members of the dummy-keys and thereby support the latter in their normal position, said bolts being outwardly projected by the depression of a key, and rigid members on said shafts arranged approximately parallel with said fingers and adapted to engage with an outwardly projected bolt of either of said fingers and actuate such finger.

GUSTAVUS A. WIKANDER.
